W. E. McCARTY

HEATER

Filed July 15, 1924

FIG. 3

Inventor
William E. McCarty
by Robert W. Jenner,
Attorney

UNITED STATES PATENT OFFICE.

WILLIAM E. McCARTY, OF ATHENS, GEORGIA.

HEATER.

Application filed July 15, 1924. Serial No. 726,119.

To all whom it may concern:

Be it known that I, WILLIAM E. McCARTY, a citizen of the United States, residing at Athens, in the county of Clarke and State 5 of Georgia, have invented certain new and useful Improvements in Heaters, of which the following is a specification.

This invention relates to heaters for dwelling houses in which open grates can 10 also be used to advantage; and it consists in the novel construction and combination of the parts hereinafter fully described and claimed whereby the heater can be taken apart when desired and portions of it used 15 in an open fire-place.

In the drawings, Figure 1 is a front view of a heater constructed according to this invention, with the front plate removed. Fig. 2 is a vertical section through the 20 heater, taken on the line 2—2 in Fig. 1, and showing the front plate in section. Fig. 3 is a front view of the frame and fire grate removed from the other parts of the heater.

A horizontal base 6 is provided, and is 25 mounted on legs 7. A frame formed of a back 8 and two sides 9 is stood loosely upon the base 6, and is open at the top and front. A rectangular chamber 10 is provided, and has a front 12 which is shorter than its back and sides. The back and sides are 30 slidable over the upper part of the frame, and rest on a ledge or projection 14 on the frame. The back, front and sides of the chamber are preferably separate plates, and are secured together by lugs 15 and bolts 16. The top of the chamber is closed by a cover 35 18 which fits over it, and the cover has an opening 19 and a flange 20 for the attachment of a stove pipe 21.

The front 12 of the chamber has two holes 22 formed in it, and a front plate 24 is 40 provided for closing the front part of the frame, leaving a draft space or opening 25 close over the base. The plate 24 has hooks 45 26 on its top edge, which engage with the holes 22, and suspend the front plate in place.

A grate 28 is secured inside the frame, and is formed of any suitable arrangement of 50 grate bars. The grate shown has horizontal bars at its front and upper part, and bottom bars 29 arranged transversely of the horizontal bars, and secured to the lowest of them and to the back of the frame. 55

When an open fire-grate can be used to advantage, the heater is taken apart, and the frame and grate as shown in Fig. 3 are stood in an open fire-place, and are used as an open grate. 60

What I claim is:

1. A heater, comprising a horizontal base, a removable frame supported on the base and open at its top and front, a grate secured inside the said frame, a removable 65 chamber supported by the said frame and provided with means for connecting it with a stove pipe, and a removable plate for partially closing the front of the frame.

2. A heater, comprising a horizontal base, a removable frame resting on the base and open at its top and front, a grate secured inside the said frame, a removable chamber closing the top of the frame and provided with a stove pipe connection, and a removable plate suspended from the front of the 70 said chamber in front of the said frame and forming a draft opening at its lower part below the grate. 75

3. A heater, comprising a horizontal base, a removable frame resting on the base and open at its top and front, a grate secured inside the said frame, a removable chamber supported by the said frame and provided with a removable cover and a stove pipe connection, the lower portions of the said 80 chamber and frame being slidably connected together, and a removable plate partially closing the front of the frame. 85

In testimony whereof I have affixed my signature.

WILLIAM E. McCARTY.
